Attorney.

UNITED STATES PATENT OFFICE.

LUDWIG POLLAK, OF ROTTERDAM, NETHERLANDS.

BUCKLE.

Application filed October 10, 1922. Serial No. 593,591.

To all whom it may concern:

Be it known that I, LUDWIG POLLAK, a citizen of the Austrian Republic, residing at Rotterdam, Netherlands, have invented 5 certain new and useful Improvements in Buckles, of which the following is a specification.

My invention refers to means for fixing sash-buckles or hair-clasps in position and 10 its particular object is a buckle or clasp which can be secured to a ribbon or belt or to the hair more easily and which is less expensive than similar devices hitherto in use.

15 The buckles or clasps as hitherto known are as a rule provided with a pin or the like hinged to it, a hook or sleeve being fixed to the back of the buckle or clasp to receive and hold the point of the pin. Quite 20 apart from the fact that the sash or belt is spoilt by piercing it with the pin, a separate hook or sleeve must be fixed to the buckle or clasp by soldering, riveting or the like.

25 In the buckle or clasp according to my invention these drawbacks are overcome in a very simple manner as shown by way of example in the drawings accompanying this specification, where I have illustrated 30 a buckle or clasp embodying my invention.

In the drawings—

Fig. 1 is an elevation,

Fig. 2 is a longitudinal section on the line 2—2 in Fig. 1, while

35 Fig. 3 shows the buckle or clasp in position on a ribbon or scarf.

Referring to the drawings, *a* is the buckle or clasp proper which may consist 40 of metal, wood, horn, ivory, tortoise-shell, mother of pearl or the like and may have any desired shape, being either plain or decorated, incrusted, etc. *b* is a hole extending through the body *a* near one of its ends and in parallel with its front and rear 45 faces and *c* is a groove or notch provided

in the other end of the body and extending substantially in parallel with the hole *b*. *d* is an elastic, substantially oval ring of steel or other metal wire extending through the hole *b* and being formed to have a larger 50 diameter somewhat smaller than the distance between the hole *b* and the notch *c*. By gripping the lateral portions of the ring *d* between two fingers it can easily be flattened and elongated to such an extent, that 55 its larger diameter gets longer than the distance between *b* and *c*. By carrying the ring thus elongated over the notch *c* and releasing the hold on its lateral portions it can be allowed to return to its original 60 shape and, in doing so, to enter the notch *c* to be retained therein by elastic pressure. In this manner the clasp or buckle can be secured on a ribbon or sash *e* or in the hair in the easiest way without requiring any 65 piercing of the fabric nor requiring any special means, besides the notch *c*, for retaining the free portion of the wire in closing position.

Obviously the wire ring, instead of being 70 oval or flat, might as well be circular or quadrangular in shape and its lateral portions might be curved in two dimensions. The body *a* may serve as the fastening means, while the ring, which may consist 75 of gold or silver wire, may form the decorative main part of the buckle.

I claim:

A buckle or clasp comprising in combination, an elongated body provided with a hole 80 near one end and a notch in parallel with the hole in the sectional face of the other end, and an elastic wire ring extending through the hole, the diameter of said ring in the middle axis of said body being slightly 85 smaller than the distance between the hole and the notch in said body.

In testimony whereof I affix my signature.

LUDWIG POLLAK.
